UNITED STATES PATENT OFFICE.

MAX SOFERMAN, OF PHILADELPHIA, PENNSYLVANIA.

ELECTRIC-FUSE CONNECTION AND TERMINAL CONTACT.

Application filed March 30, 1926. Serial No. 98,504.

In the manufacture of electric fuse plugs it has usually been the custom to insert the fuse wire and solder it to the end terminal contact and to the electric current conducting metallic screw threaded shell or sleeve. This method of procedure is tedious and expensive, often resulting in insecure connections rendering the plugs of no value. In view of the above mentioned method of construction, numerous devices have been invented to facilitate the production of electric fuse plugs. Some of said devices have included attaching means for fuse wire inserted in the end of the fuse plug body. None of said devices has been entirely satisfactory in securely retaining the fuse wire and insuring proper contact with the screw threaded shell and central contact under all conditions. One object of my invention is to provide an improved construction which will facilitate and reduce the cost of manufacture of electric fuse plugs or like structures and at the same time insure good and permanent contacts to properly conduct the electric current.

Another object is to so construct and apply my invention that it is unnecessary to use solder in order to effect proper connection of the parts.

These objects and other advantageous ends which will be set forth hereinafter, I attain in the following manner, reference being had to the accompanying drawing in which

Figure 1 is a central longitudinal sectional elevation of a fuse plug having my invention applied thereto,

Figure 2 is an elevational side view of said plug with certain of the parts removed,

Figure 3 is a bottom view of said plug with the metallic screw threaded shell removed,

Figure 4 is a section taken on the line 4—4 of Figure 1,

Figure 5 is a fragmentary bottom plan view showing the shape of the aperture in the lower end of the plug body,

Figure 6 is a perspective view showing certain of the parts assembled and ready to be inserted within a fuse plug body, and

Figure 7 is a rear elevational view of a part of my invention as shown in Figure 6.

Referring to the drawing, 7 represents a fuse plug body which is made of porcelain or other suitable insulating material, said

body having a chamber 8 which leads downwardly from its top as shown in Figure 1, the bottom or base 9 of said body having a hole or aperture 10 extending upwardly 60 from its lower face and communicating with the chamber 8. The aperture 10 is substantially rectangular and has an off-set notch 11 as clearly shown in Figures 4 and 5, said off-set notch preferably being located 65 centrally between the two side walls 12 and 13 of the aperture 10 for a purpose hereinafter described.

The body 7 has two outer annular ledges or shoulders 14 and 15 both of which face 70 downwardly and are of different diameters. The body 7, between the ledges 14 and 15, has formed thereon a screw thread 16 upon which is screwed a metallic screw threaded sleeve 17, the outer screw threads of said sleeve 17 serving to allow the fuse plug to be inserted within any receptacle into which it is desired to place the fuse plug in the usual manner of inserting fuse plugs.

The body 7 has a channel 18 which, at its 80 top, communicates with the chamber 8 and at its lower end, communicates with a groove 19 formed in the outer face of the body 7. The groove 19 extends downward to the ledge 15 and includes an angular deflecting surface portion 20 at a position below the ledge 14 as shown in Figure 1, said deflecting surface portion 20 being for a purpose hereinafter described.

A unitary terminal contact clamp 21, 90 which is made of a single piece of sheet metal, is split and pressed to produce the following structure. A transversely extending arm portion 22 has, depending therefrom, a central tongue 23 which is bent in the direction of its length in the form of a compound or ogee curve to produce an inwardly bulged portion 24. The lower end of the tongue 23 merges into a plate portion 25. Two lateral fingers 26 and 27 depend from the arm 22 at opposite sides of the tongue 23 and are bulged or curved inwardly to a greater extent than the portion 24 of the tongue 23 so that the free end portions 28 and 29 of said fingers 26 and 27 extend directly over the top surface of the plate 25. Projecting upwardly from the arm 22 is a split binding cuff 30 adapted to embrace and firmly squeeze and clamp one end portion of an elongated fuse strip 31.

A second unitary terminal contact clamp 32, which is made of a single piece of sheet

metal, is split and pressed to produce the following structure. A contact flange foot 33 has two oppositely extending lateral end portions 34 which preferably extend upwardly at a slant to the central portion 35 as clearly shown in Figures 2 and 6. A split binding cuff 36 extends upwardly from the central portion 35 and this binding cuff 36 embraces and squeezes the opposite end portion 34 of the fuse strip 31 so as to firmly clamp the same.

Any suitable top closure can be provided for the fuse plug and in the present instance, I have shown a disk 37 which may be 15 made of mica with a surrounding cap ring 38.

In assembling the structure, considering that the sleeve 17 and top closure structure are not connected to the fuse plug body, the 20 fuse strip 31 with the clamps 21 and 32 connected thereto is applied in the following manner. The device 32 is inserted upwardly through the aperture 10 into the chamber 8, the wide portion of said aperture 25 10 being sufficient to allow the foot 33 to freely pass therethrough. The fuse strip 31 is sufficiently stiff to support the device 32 so that a workman can easily and quickly push the device 32 upwardly through the 30 chamber 8 to such extent that he can then grasp the device 32 from the top of the chamber and pull or drag the device 21 until the cuff 30 passes through the aperture 10. The workman can then guide and push the 35 arm 22 into the aperture 10 with the tongue 23 within the off-set notch 11, the side edges of the fingers 26 and 27 engaging the walls 12 and 13 of the aperture while the outer faces of the fingers 26 and 27 engage the wall 39 40 of said aperture 10 so as to slightly compress and flex said fingers 26 and 27. This action will also cause the rear face 40 of the tongue 23 to contact with the wall 41 of the notch 11 at different points within the length of the 45 bulged portion 24 as clearly shown in Figure 1, and the plate 25 will abut the bottom surface of the base 9 and overlap the aperture 10 as clearly shown in Figures 1, 3 and 4. Also by the construction, including the 50 bulged portion 24 of the tongue 23, a part of said tongue will overlap the surface 42 which forms the bottom of the chamber 8, said overlapping being shown at 43 in Figure 1, the cuff 30 occupying a position against the side wall 44 of said chamber 8. In this 55 manner the device 21 is secured against accidental displacement and the plate 25 will serve as an electric contact plate when the fuse plug is inserted in a receptacle in the usual manner. I preferably slightly slant the plate 25 relatively to the bottom surface of the base 9 as shown in Figure 1, with the lower ends of the fingers 26 and 27 abutting or nearly abutting the top surface of the 60 plate 25 so that a slight resiliency is given

to the plate 25, with a resistance produced by the resilient fingers 26 and 27, so as to insure a good electrical contact when the fuse plug is inserted within a receptacle.

After the device 21 has been inserted as 70 above described, the workman then bends the fuse strip 31 and pushes the device 32 downwardly through the channel 18. During this action the foot 33 will engage the deflecting surface 20 so that the device 32 75 will be deflected outwardly at a position below the ledge 14 and the workman can then pull or drag the device downwardly into the groove 19 and place the foot 33 under the ledge 15, the structure being such that said 80 foot 33 is slightly off-set to the cuff 36 which allows the cuff 36 to remain in the groove 19 with the extreme ends of the portion 34 engaging the ledge 15 as clearly shown in Figure 2.

With the parts in said position the sleeve 17 is screwed on to the body 7 until the lower inturned flange 45 of said sleeve abuts and compresses the foot 33 thereby holding the foot 33 firmly against the ledge 90 15. Furthermore, the internal diameter of the sleeve 17 is preferably such as to cause contact with the cuff 36 adjacent the split 95 43 and thereby firmly hold said cuff 36. After the sleeve 17 has been applied as just described, portions of the flange 45 may be pressed upwardly into notches 47 in the shoulder 15 to guard against accidental rotation of the sleeve 17 relatively to the body 7. The top closure can then be applied and 100 the plug is ready for use.

It has been found that the fuse with the devices 21 and 32 can be attached in a few seconds without requiring the soldering of any of the parts.

Furthermore, by having the tongue 23 located within the notch 11 with the fingers 26 and 27 abutting the walls 12, 13 and 39, a structure is produced free from detrimental vibration and accidental dislodgment, and not only is there a general three-point contact produced by the portions 23, 26 and 27 but there is an overlap present such as the overlap of the part 43, which renders the attachment additionally secure.

Having thus described my invention what I claim as new and desire to secure by Letters Patent is:

1. In a fuse holder, a body structure having an aperture; and a fuse connecting device having fingers arranged in different lateral flexing planes and bearing upon the wall of said aperture to hold said device relatively to said body structure.
2. In a fuse holder, a fuse; a body structure having an aperture; and a fuse connecting device having a split portion providing parts bent in opposite directions to resiliently bear upon portions of the wall of said aperture, said device having a split 125 130

fuse binding cuff around said fuse at a position remote from the flexing zone of said resilient bearing parts.

3. In a fuse holder, a body structure having an aperture; and a fuse connecting device having portions including fingers arranged in different lateral flexing planes and bearing upon the wall of said aperture to hold said device relatively to said body structure, one of said portions being extended to provide a contact plate outside of said body structure.

4. In a fuse holder, a body structure having an aperture; and a fuse connecting device having portions arranged in different flexing planes and bearing upon the wall of said aperture to hold said device relatively to said body structure, one of said portions being extended to provide a contact plate outside of said body structure, the other portion terminating adjacent said plate at a position remote from the junction of said first portion with the plate to provide a resilient backing for the plate.

25 5. In a fuse holder, a fuse; a body structure having an aperture; and a fuse connecting device having a split portion including a tongue terminating in a contact plate and fingers at opposite sides of said tongue, said fingers and tongue being bent to bear upon the wall of said aperture, said device

at a position remote from said split portion having a cuff in clamping contact with said fuse.

6. In a fuse holder, a body structure having an outer ledge and a channel leading to the outside thereof; a fuse; a fuse contact clamp secured to said fuse and adapted to be projected through said channel to the outside of said body structure, said device having a foot portion with a resilient part adapted to engage said ledge; an electric contact member connected to the outside of said body structure and adapted to hold said resilient part of said foot against said ledge; and an outer contacting shell adapted to press said foot against the ledge.

7. In a fuse holder, a fuse; a body structure having an aperture with an off-set notch within the width thereof; and a fuse connecting device having a split portion including a tongue terminating in a contact plate and fingers at opposite sides of said tongue, said tongue being located within said off-set notch, said fingers and tongue being bent to bear upon opposite portions of the wall of said aperture, said device being secured to said fuse.

In testimony whereof, I have signed my name to this specification.

MAX SOFERMAN.
